(57) **CLAIM**

The ornamental design for a camera ball and socket mount adapter arm, as shown and described.

DESCRIPTION

FIG. 1 is a front and right perspective view of a camera ball and socket mount adapter arm;

FIG. 2 is a rear and left perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines in the drawings depict portions of the camera ball and socket mount adapter arm that form no part of the claimed design.
